ATTACHMENT FOR A WASHING MACHINE
LEG

Elmer Fuerst, Cincinnati, Ohio

Application April 25, 1950, Serial No. 9,457

Term of patent 14 years

(Cl. D49—1)

To all whom it may concern:

Be it known that I, Elmer Fuerst, a citizen of the United States, residing at Cincinnati, in the county of Hamilton and State of Ohio, have invented a new, original, and ornamental Design for an Attachment for a Washing Machine Leg, of which the following is a specification, reference being had to the accompanying drawing forming part thereof, in which:

Fig. 1 is a plan view of an attachment for a washing machine leg showing my new design.

Fig. 2 is a rear view of the same.

Fig. 3 is a side view of the same.

Fig. 4 is a vertical sectional view of the same, taken in the plane of the line 4—4 of Fig. 2.

I claim:

The ornamental design for an attachment for a washing machine leg, substantially as shown.

ELMER FUERST.
